CLAIM

The ornamental design for a control valve for sprinklers, substantially as shown and described.

DESCRIPTION

FIG. 1 is a perspective view taken from the top, front, and left side of a control valve for sprinklers showing our new design;

FIG. 2 is a right side elevational view thereof;

FIG. 3 is a front elevational view thereof;

FIG. 4 is a rear elevational view thereof;

FIG. 5 is a bottom plan view thereof;

FIG. 6 is a perspective view taken from the top, front, and left side of a modified form of the control valve for sprinklers shown in FIG. 1;

FIG. 7 is a right side elevational view of FIG. 6;

FIG. 8 is a front elevational view of FIG. 6;

FIG. 9 is a rear elevational view of FIG. 6; and

FIG. 10 is a bottom plan view of FIG. 6.

The broken line representation of an electric connection in FIGS. 6 through 9 is for purposes of illustration only.
